Primary Examiner—Ruth McInroy(74) *Attorney, Agent, or Firm*—Fitch, Even, Tabin & Flannery**CLAIM**

We claim the ornamental design for a power wailer, as shown and described.

DESCRIPTION

FIG. 1 is a perspective view of a power wailer showing a first embodiment of our new design and showing the pad thereof in phantom;

FIG. 2 is a top plan view of the power wailer of FIG. 1; FIG. 3 is a left side elevational view of the power wailer of FIG. 1;

FIG. 4 is a right side elevational view of the power wailer of FIG. 1;

FIG. 5 is a front elevational view of the power wailer of FIG. 1;

FIG. 6 is a rear elevational view of the power wailer of FIG. 1;

FIG. 7 is a bottom plan view of the power wailer of FIG. 1 with the pad removed;

FIG. 8 is a perspective view of a power wailer showing a second embodiment of our new design having a speed-control switch adjacent the top thereof;

FIG. 9 is a top plan view of the power wailer of FIG. 8; FIG. 10 is a left side elevational view of the power wailer of FIG. 8; and,

FIG. 11 is a rear elevational view of the power wailer of FIG. 8.

The broken line showing of a pad in all views is for illustrative purposes only and forms no part of the claimed design. The only difference in the second embodiment is the addition of the switch on the top of the wailer.
